UNITED STATES PATENT OFFICE.

JAKOB NIEDERER, OF HEIDEN-BISSAU, SWITZERLAND.

BUTTON.

No. 895,293.

Specification of Letters Patent.

Patented Aug. 4, 1908.

Application filed January 31, 1908. Serial No. 413,543.

To all whom it may concern:

Be it known that I, JAKOB NIEDERER, a citizen of the Republic of Switzerland, residing at Heiden-Bissau, in the county of Appenzell and Republic of Switzerland, have invented certain new and useful Improvements in Buttons, of which the following is a specification, reference being had therein to the accompanying drawings.

10 This invention relates to buttons of that style commonly known as "bachelor buttons".

The primary object of my invention is, to provide a simple and inexpensive button 15 that can be easily and quickly attached to a garment or a piece of material.

Another object of this invention is to provide a two-part button, wherein a novel 20 spring is employed for retaining the parts of the button together.

With the above and other objects in view, the invention consists in the novel construction, combination and arrangement of parts to be presently described and then specifically 25 pointed out in the appended claims.

In the drawing: Figure 1 is a cross sectional view of my button, partly in elevation, Fig. 2 is a bottom plan of a cap forming part of the button, Fig. 3 is a top plan of the same, Fig. 4 is a cross sectional view, Fig. 5 is a plan of a spring used in connection with the button, Fig. 6 is a cross sectional view of the same, Fig. 7 is a plan of a cushion used in connection with the button, and Fig. 8 is a 35 plan of a portion of the button.

A button constructed in accordance with my invention comprises in its entirety four parts, and consists of a cap or outer head, a disk or inner head carrying a shank, a securing member which connects the shank of said disk or inner head with the cap or outer head, and a cushion interposed between the cap or outer head and the securing member. The cap or outer head 1 is substantially in the 40 form of a disk and is provided with a peripheral inwardly turned flange 2 forming an annular groove 3 at the periphery of the inner face of said cap or outer head, the said cap or outer head is also dished centrally to form a 45 projection 4 on the outer face of such cap or head, and a concave seat or depression on the inner face of said head centrally thereof. The inner head 13 of the button is also in the 50 form of a disk, and in practice is generally 55 made of less diameter than the outer head or cap of the button, and carries a centrally-

disposed shank 11 provided on its free end with a head 12, which head, when the sections of the button are connected together, is seated in the depression or seat 5 in the outer 60 head or cap 1.

My invention particularly resides in the novel securing member by means of which the above described elements of the separable button are connected and securely held 65 together. This securing member is formed from a disk of thin metal which is dished sufficiently to make the same somewhat cup-shaped in form as seen in Figs. 1 and 6. I make cuts or incisions in this member extending from the periphery thereof inwardly, and arranged in pairs, the outer ends of each pair of incisions or cuts being in juxtaposition, with one cut of each pair extending in the opposite direction to the other cut of the 70 pair, and the material bounded by the said cuts or incisions is looped or bent over towards the center of the disk so as to form resilient retaining arms 9, the free ends of 75 which slightly overlie the central aperture 10 which is made in said disk. The said aperture 10 is made of a diameter which will allow the head 12 to pass therethrough, and the free ends of the resilient retaining arms 9 overlying this aperture, it will be observed that the 80 head 12 must be forced through between the free ends of the arms 9 in order to pass the same, and after the head 12 has passed the resilient arms, the latter will spring or snap back so as to lie underneath the shoulder of 85 the head 12 as seen in Fig. 1 of the drawings, and thus connect the outer and inner heads of the button together.

The portions 8 of the disk from which the securing member 1 is formed that lie between the incisions made in the periphery of the disk are somewhat segment shaped in form; these portions constitute arms which are so bent as to cause the periphery thereof to enter the groove 3 of the cap or head 1 as 95 seen in Fig. 1 of the drawings, whereby the securing member is firmly fixed to the cap or head member 1. Besides serving as the means for connecting the securing member to the cap or head 1, these portions or arms 8 of the securing member also serve to fixedly 100 secure to the inner face of the cap or head 1, a disk 6 which is made of flexible material and acts as a cushioning member to prevent any rattling of the parts when in connected position. The said cushioning member 6 is provided with a central opening 7 so as to re- 105 110

ceive the head 12 of the shank 11, and besides being held by the arms 8, it is to be noted that the resilient arms 9 of the securing member also impinge the said cushioning member 5 as seen in Fig. 1 so that the latter is firmly secured in its position and all danger of rattling between the parts is obviated. Still further, it will be observed that this disk 6 acts as a cushion for the arms 9 as the same 10 spring back into position upon forcibly withdrawing the head 12 from its seat 5, preventing the metallic arms 9 from striking the metallic cap or head and possibly injuring the arms 9.

15 The manner of connecting the separable buttons of this character to a garment is well known in the art, and is believed to require no description.

Attention is called to the fact that owing 20 to the construction of the securing member the shank 11 and its connected disk is firmly held connected to the cap or outer head 1 owing to the spring or resilient arms 9 engaging back of the head of the shank, and 25 normally tending to force the latter towards the cap 1, and holding the head of the shank firmly nested in its seat.

Having now described my invention what I claim as new, is:-

30 A button, comprising an outer head member embodying a disk provided on its inner face centrally thereof with a seat and having an inturned peripheral flange forming an

annular groove around the circumference of the inner face, a cushioning disk held in said 35 groove and having a central opening registering with the seat in said outer head member, an inner button head, a shank projecting centrally therefrom and having a head on its outer end, and a securing member for 40 connecting the outer head to the said shank, said securing member comprising an apertured disk provided with incisions or cuts extending inwardly from the periphery of the disk in pairs, the outer ends of the outer 45 cuts or incisions of each pair being in juxtaposition and one cut or incision of each pair extending in the opposite direction to the other cut or incision of the same pair, the portion of the disk bounded by each pair of 50 cuts being bent inwardly and bowed to form spring arms, the free ends of which overlie the central opening in said disk and engage back of the head on said shank, and the outer faces of which engage the cushioning 55 disk, the remaining peripheral portion of said disk being received in the groove in the outer head and holding the cushioning disk against the latter.

In testimony whereof I affix my signature 60 in the presence of two witnesses.

JAKOB NIEDERER.
